UNITED STATES PATENT OFFICE.

JOHN C. BROOKS, OF PATERSON, NEW JERSEY.

WOVEN PILE FABRIC.

1,113,098.

Specification of Letters Patent.

Patented Oct. 6, 1914.

Application filed March 25, 1913. Serial No. 756,706.

To all whom it may concern:

Be it known that I, JOHN C. BROOKS, a citizen of the United States, and a resident of Paterson, in the county of Passaic and 5 State of New Jersey, have invented a new and useful Improved Woven Pile Fabric, of which the following is a specification.

My invention relates to woven pile fabrics, and particularly to an improved weave 10 for carpet fabric, such for example, as Axminster or moquette, tapestry, Brussels, velvet or Wilton.

The especial objects of this invention are to provide such pile fabrics with a high 15 simulation of oriental woven fabrics.

In the drawings Figure 1 is an enlarged, open weave, longitudinal section, through the weft, of my improvement illustrative of an Axminster and tapestry. Fig. 2 is a 20 similar view of my improvement illustrative of Brussels, Wilton or velvet. Fig. 3 is a right hand end view of Fig. 1, but showing a second body-warp thread and pile tuft. Fig. 4 is a perspective view showing 25 the right hand end of Fig. 2.

Referring to Fig. 1, *a* is a body-warp thread and *b* a continuous pile-warp-thread, printed as is customary in tapestries; for pick 1 the thread *b* crosses over and is bent 30 below thread *a* and secured by a weft-thread *C*, thread *b* is then raised in a loop, *d*, and again lowered and secured by a pick of weft, 2; thread *b* is then crossed over thread *a* and lowered at the opposite side 35 and secured by a pick of weft, 3; thread *b* is then raised in a loop, *e*, and again lowered and secured by a pick of weft, 4; which completes the weave.

The cutting of the loops, as well understood, would change the product to tapestry velvet, as picks 5, 6, 7, 8 and 9 indicate. The length of thread forming the pile tufts held in by picks 6, 7, 8 and 9 can be inserted from separate warp spools, as is customary in Axminster weaving, with loom mechanism such, for instance, as is shown in my application Serial No. 720,603, filed September 16, 1912.

Referring to Fig. 2, *f* is a body warp 50 thread, *g* and *h* a frame of continuous pile warp threads, as is customary in weaving Brussels and Wiltons; for pick 1 both threads, *g* and *h*, are bent over body thread *f*, and passed below said thread, and se-

cured by a pick of weft 1, one of the threads, 55 in this instance *g*, is raised into a loop and again lowered and secured by a pick of weft, 2; both threads, *h*, *g*, are then crossed over thread *f* then lowered and secured by a pick of weft, 3; one of the desired threads 60 in this instance *h*, is raised into a loop and again lowered and secured by a pick of weft, 4; which completes the weave.

The cutting of the loops, as illustrated between picks 5, 6, and 7, 8, changes the fabric from Brussels to a Wilton or velvet pile.

It is observable that, with the above described fabric, the pile can be driven very close, and a fine appearing oriental simulation obtained both as regards the face and 70 back of the fabrics; and an exceedingly durable fabric obtained for wear in which the pile is not likely to pull out either during its manufacture or after use. It will be also observed that the body warp and weft is 75 absolutely covered by the pile threads, on the face, and, practically, also on the back of the fabric.

In order to produce an equally durable fabric, but with less density of pile, auxiliary binding warp-threads, *i*, *j* can be employed as illustrated in Fig. 1, these threads crossing each other after each pair of weft threads.

While I have shown a fabric of only one 85 ply extra plies may be added to form any desired back, thus it is obvious that changes may be made in constructing my improved fabric bodily, by those skilled in the art, without departing from the scope of my invention. I do not wish therefore to be limited to the absolute construction I have herein shown and described, but:—

What I do claim, and desire to secure by Letters Patent of the United States is:— 95

1. A pile fabric having body warp threads, weft threads and short separate tuft threads, each of which is bent over a body warp thread and passed under two 100 separate weft threads.

2. A pile fabric having a plurality of body warp threads, weft threads situated entirely below the warp threads, and pile tufts each passing under two adjacent weft threads and over a warp thread.

3. A pile fabric having a plurality of body warp threads, weft threads, and pile tufts each passing under two adjacent weft

threads and the portion of each tuft between the weft threads passing over a warp thread.

4. A pile fabric having a plurality of body warp threads, weft threads, and pile tufts each passing under one weft thread over a warp thread and under an adjacent weft thread.

5. A pile fabric having a plurality of warp threads, weft threads situated entirely below the warp threads, and pile tufts

bound into the fabric by the weft threads, the two free ends of each tuft being situated on opposite sides of a warp thread.

In testimony whereof I have hereunto set my hand, in the presence of two subscribing witnesses.

JOHN C. BROOKS.
